UNITED STATES PATENT OFFICE

GUARD FOR NOZZLE SPRAY DEFLECTORS

Fred W. Wahlin, Oak Park, Ill., assignor to Spraying Systems Co., Chicago, Ill., a corporation of Illinois

Application December 7, 1948, Serial No. 63,925

3 Claims. (Cl. 299—121)

1

My invention relates to a guard for the spray deflecting extension of a nozzle of the type shown in my application, Serial No. 581,582, filed March 8, 1945, now Patent No. 2,530,671 issued on October 3, 1950, wherein the nozzle has an extension projecting beyond the discharge orifice of the nozzle and provided with a surface along which the stream is discharged from the nozzle orifice, and by which the stream is deflected laterally and spread into a flat stream of progressively increasing width.

Inasmuch as any imperfections in the surface of the deflector, and especially at the edges thereof where the stream takes off therefrom, impairs the accuracy of the spray pattern it is important to protect said surface and edges from injury, and it is the principal object of my invention to provide a simple, convenient and inexpensive guard which affords such protection.

Other objects of the invention are to construct the guard so that it is readily attachable to and removable from the nozzle; to hold the guard securely in position so that it will not become displaced or otherwise interfere with the deflected stream; and to provide a guard which does not materially add to the weight of the nozzle nor obstruct observation of the operation of the nozzle, all these and other objects being accomplished as pointed out more particularly hereinafter and as shown in the accompanying drawing, in which:

Fig. 1 is a side view of a deflector nozzle looking at the deflector face side thereof and showing a guard mounted thereon in accordance with my invention;

Fig. 2 is an outer end view of the nozzle and guard of Fig. 1;

Fig. 3 is an inner end view of the nozzle and guard of Fig. 1 with a portion at the inner end of the guard broken away; and

Fig. 4 is a longitudinal sectional view of the nozzle and guard taken on the line 2—2 of Fig. 1.

In the drawing, the reference numeral 10 indicates the nozzle as a whole, which comprises a body 11 of square cross section with an opening 12 therethrough which is reduced at one end of the nozzle body, hereinafter referred to as the outer end, to a relatively small orifice 13 which constitutes the discharge orifice of the nozzle.

At the inner end of the nozzle body the opening 12 is internally threaded as at 14, for connection thereto of a pipe, hose or the like through which liquid is supplied to the nozzle. At its outer end the nozzle body 11 has a relatively long integral extension 15 projecting forwardly there-

from at one side of the discharge orifice 13 and this extension 15 has a deflector face 16 along which the stream is discharged from the orifice 13, this deflector face being curved lengthwise as shown in Fig. 4 so as to deflect the stream issuing from the orifice 13 laterally and cause the stream to assume a progressively flattened and divergent form assumed by the flattening stream 17 so as to produce a flattened spray pattern of desired spread.

It is important, for accuracy of the spray pattern, that the deflector surface 16, and especially the marginal edges 18 thereof where the stream 17 passes off of the deflector face, be free of any inaccuracies or defects and as such face and edges may become damaged in handling or in use, a guard is provided, in accordance with the present invention, to safeguard the deflector face and edges of such nozzles or similar nozzles against accidental injury.

This guard, in its preferred form, comprises an open coil helical spring 19 of such circumferential size to accommodate the nozzle extension 15 freely therein and provided with facilities at the opposite ends for detachable engagement respectively with the nozzle body and the outer end of the extension 15 so as to hold the spring outstretched and in a fixed position wherein it does not interfere with the operation of the nozzle.

Preferably for attaching the inner end of the guard spring 19 to the nozzle body 11, said spring is formed at its inner end with several close adjoining coils 20 of reduced diameter and the inner end portion of the nozzle body 11 is of a reduced transverse size to accommodate said coils 20 thereon and to provide stop shoulders 21 against which said coils 20 abut.

With the body 11 of the square cross section form disclosed herein, sufficient reduction in size of the body 11 to accommodate the small diameter coils 20 may be provided by merely removing or omitting corner portions of the body as indicated at 22 to form adequate shoulders 21 and at the same time leave sufficient of the flat sides of the square beyond the coils 20 for application of a wrench thereto for attaching the nozzle to a pipe or other conduit on which the nozzle is to be mounted.

At the other end of the guard spring 19 the latter terminates in a relatively flat end coil 23 with the end portion of the wire bent radially inward as shown at 24 to the center of the coil where the extreme end portion of the wire is bent axially toward the other end of the guard spring as shown at 25, and the outer end of the deflector

extension 15 is formed with a socket 26 to receive the wire end 25 and a groove 27 leading radially from the outer end of the socket 26 in which a portion of the radial wire 24 seats to hold the guard spring against turning movement around the nozzle and deflector extension.

This radial groove 27 extends in a direction toward the side of the extension 15 opposite the deflector face 16 side thereof so that the radial wire 24 will not obstruct the path of the spray 17 discharged from the end of the deflector face and the outer end coils of the spring guard 19 are, of course, of sufficient diameter to afford ample clearance for free and unobstructed passage of the spray therethrough.

For applying the guard spring 19 on the nozzle, it is merely necessary to introduce the body end of the nozzle between the two last widely spaced convolutions of the spring at the outer end of the latter and thereupon move the nozzle body 11 and extension 15 lengthwise within the spring until the reduced inner end of the nozzle body is engaged within the coils 20 of reduced diameter at the inner end of the spring 19 and then stretch the spring outwardly and engage the wire end 25 in the socket 26 with the radial wire 24 seated in the groove 27, said spring 19 being of such normal length that it is stretched under sufficient tension, when thus applied, to be held thereby securely against displacement.

For removal of the guard spring, it is merely necessary to release the outer end of the spring from the socket 26 and groove 27 and then withdraw the extension 15 and nozzle body 11 endwise between the two last widely spaced convolutions at the outer end of the spring.

Thus the guard is simple and inexpensive, readily attachable and removable, is of light weight, permits observation of the nozzle operation at all times, effectively guards the deflector face and edges and does not interfere with the nozzle operation.

While I have shown and described my invention

in a preferred form, I am aware that various changes and modifications may be made therein without departing from the principles of my invention, the scope of which is to be determined by the appended claims.

I claim as my invention:

1. The combination of a nozzle having a deflector projecting therefrom in the path of discharge from the nozzle, said nozzle and deflector each having a seat, and a deflector guard comprising an axially distended helical spring surrounding the deflector and having the opposite ends thereof engaged respectively in said seats.

10 2. The combination of a nozzle having a deflector projecting therefrom in the path of discharge from the nozzle, of a deflector guard comprising a helical spring surrounding the deflector and annularly engaged at one end with the nozzle, said spring being axially distended and having an axially disposed extension at the other end engaged with the outer end of the deflector.

15 3. The combination of a nozzle having a deflector projecting therefrom in the path of discharge from the nozzle, said nozzle having an annular seat and said deflector having a recess in the outer end, and a deflector guard comprising an axially distended helical spring surrounding the deflector and having a coil at one end engaged in said annular seat and having a central portion at the other end engaged in said recess.

FRED W. WAHLIN.
